W. I. HAWKINS

SHIRT SLEEVE

Filed Jan. 2, 1923

FIG. 1

FIG. 2

FIG. 3

INVENTOR
W. I. HAWKINS

BY *Wright & Chaney*

ATTYS.

UNITED STATES PATENT OFFICE.

WASHINGTON I. HAWKINS, OF SAN FRANCISCO, CALIFORNIA.

SHIRT SLEEVE.

Application filed January 2, 1923. Serial No. 610,213.

To all whom it may concern:

Be it known that I, WASHINGTON I. HAWKINS, a citizen of the United States, residing at San Francisco, in the county of 5 San Francisco and State of California, have invented new and useful Improvements in Shirt Sleeves, of which the following is a specification.

This invention resides in the provision of 10 simple and inexpensive means for shortening the sleeves of men's shirts so as to draw into concealed position in the coat sleeves, the cuffs of said shirt sleeves, whereby when the cuffs are soiled they may be thus hidden 15 and also, clean cuffs may, in this manner, be protected against becoming easily soiled.

The primary object of the invention is to provide sleeve shortening means as described which may be provided by the simple ex- 20 pediency of forming a button hole in each sleeve and by the use of the placket buttons as now generally used, to close the sleeve plackets of the present day shirt.

The invention possesses other advantages 25 and features some of which, with the foregoing will be set forth at length in the following description where I shall outline in full that form of the invention which I have selected for illustration in the drawing ac- 30 companying and forming a part of the present specification. In said drawing I have shown one form of the construction of my invention, but it is to be understood that I do not limit myself to such form since 35 the invention as expressed in the claim may be embodied in a plurality of forms.

Referring to the drawing:

Fig. 1 is a perspective view of an ordinary shirt sleeve with attached cuff showing 40 the extra button hole necessitated by my invention.

Fig. 2 is a perspective view of the sleeve and cuff showing the arrangement thereof when my invention is carried out.

Fig. 3 is a perspective view of a modified form of the invention.

In carrying out my invention with the ordinary men's shirt having, as shown in the drawing, a sleeve 1, attached fold back cuff 2, placket 3, placket reinforcing strip 4, placket button 5 and button-hole 6, I form 50 a button-hole 7 in the sleeve preferably through the inner end portion of the strip 4, which portion is located beyond and in line with the closed end of the placket. I do not wish to limit myself to the arrange- 55

ment and position of the extra button-hole, and since it is obvious that this extra button-hole may be provided in various ways to receive the button 5, and effect a shortening of the sleeve, I wish it understood that I may resort to any arrangement providing for, or any location of said button-hole, providing that upon buttoning of the button 5 in said hole, the sleeve will be shortened and the cuff drawn upwardly on the arm. However, the arrangement shown in the drawing is desirable since it is simple and inexpensive and provides for my invention at the least expense. 60 65 70

To shorten the sleeve to hide a soiled cuff or to protect a fresh cuff, it is only necessary to button the button 5 in the hole 7. This may be done with the placket open or unbuttoned, as well as when the placket is 75 closed or buttoned, although a neater folding and sleeve shortening may be effected when the placket is closed, as shown in Fig. 2.

The shortening is best effected by grasping 80 the sleeve near the button 5 and pulling up on the cuff so as to bring said button through the placket and under and then through the button-hole 7. This may be easily done and provides a smooth fold as 85 shown at 8. In the ordinary shirt the placket button is located from approximately three to five and one-half inches from the inner end of the placket or inner end of the reinforcing strip and the buttoning of 90 the placket button into a button-hole located near the inner end of the placket will provide for a shortening of the sleeve sufficient to draw the cuff to a well concealed or protected position in the coat sleeve, this withdrawal of the cuff being substantially equal to the distance between the placket and buttons and extra button-hole. 95

With my invention the placket button has 100 a double function and this is an important point in that extra elements such as usually employed in shirts for shortening sleeves are not necessary. It is only necessary to provide in the ordinary shirt sleeve an extra button-hole, to carry out my invention. Due 105 to the simplicity of my invention, its absence of extra buttons, tabs and other elements, the sleeve of my invention will fold without bulging, is neat, easier to operate and generally speaking, is a substantial improvement over other sleeves having shortening means thereon. 110

In instances where, with the cuff exposed, the sleeves are too long, by buttoning the placket button into the extra button-holes, the sleeves will be shortened to suit the 5 wearer.

In Fig. 3, I have shown a modified form of my invention wherein the placket reinforcing strip 9 is folded to form a tab 10. The tab 10 has a button-hole 11 therein and this 10 button-hole is adapted to receive the usual 15 placket button 12. One advantage in this 20 form of the construction is that it is unnecessary to button through the placket opening, it only being necessary to make a transverse 25 fold of the sleeve and to dispose the placket button beneath the tab, as is obvious from an inspection of the drawings, instead of having to bring the button through the placket opening and underneath the reinforcing strip, as in the previously described 30 form of the invention. In attaching the reinforcing strip, it is folded transversely at a point spaced inwardly from its outer or upper end and stitched, as shown, so that the 35 tab is provided. The tab may also be fastened on one side to the strip and as shown,

is folded under one side of the placket opening as at 13. This serves to hold the tab more or less flat against the top of the reinforcing strip.

30

Various ways of providing the tab on the reinforcing strip may be resorted to but I prefer to provide the tab by a transverse fold of the strip intermediate of its ends and by the longitudinal fold so as to bring a 35 portion of the tab on the under side of the sleeve.

I claim:

A shirt sleeve having a placket and two button-holes extending through the sleeve, 40 one hole being located on one side of and intermediate of the ends of the placket and the other located adjacent the upper or inner end of the placket and a button on the side of the placket substantially opposite to the first named button-hole adapted to button from the inner side of the sleeve through both holes, the first hole so as to close the placket and the second hole after a transverse fold of the sleeve so as to shorten the 45 sleeve.

WASHINGTON I. HAWKINS.
